(57) **CLAIM**

The ornamental design for a microphone, as shown and described.

DESCRIPTION

FIG. 1 is a top perspective view of a microphone showing my new design;
FIG. 2 is a front view thereof;
FIG. 3 is a rear view thereof;
FIG. 4 is a left elevational side view thereof;
FIG. 5 is a right elevational side view thereof;
FIG. 6 is an enlarged top elevational view thereof;
FIG. 7 is an enlarged bottom elevational view thereof;
FIG. 8 is a top perspective view of the microphone shown connected to a USB plug; and,
FIG. 9 is a bottom perspective view of the microphone. The broken line showing of the USB plug in FIG. 8 depicts environment and forms no part of the claimed design. The microphone's electrical wire is shown with a symbolic break in its length. The appearance of any portion of the electrical wire after the break line forms no part of the claimed design.
